Specification of Letters Patent.

Patented Apr. 4, 1922.

Application filed June 28, 1920. Serial No. 392,239.

To all whom it may concern:

Be it known that I, ADOLPH H. C. HORNBOSTEL, a citizen of the United States, residing at Deshler, in the county of Thayer 5 and State of Nebraska, have invented certain new and useful Improvements in Computing Devices, of which the following is a specification, reference being had to the accompanying drawings.

10 This invention relates to certain improvements in computing devices and it is primarily an object of the invention to provide a novel and improved device of this general character which can be employed 15 with convenience and facility to compute the interest due within a given period of time upon a given sum of money at a certain rate of interest or per cent.

It is also an object of the invention to 20 provide a novel and improved device of this general character comprising a plurality of members rotatable about substantially a common axis and wherein the peripheries of said members are provided with coacting 25 indicia to effect the requisite computation.

Another object of the invention is to provide a novel and improved device of this 30 general character comprising a plurality of relatively rotatable members, together with means whereby said members may be caused 35 to rotate in unison or separately in accordance with the requirements of practice.

Furthermore, it is an object of the invention to provide a novel and improved device 40 of this general character including a plurality of members rotating about a common axis, together with means whereby said members normally are adapted for unitary rotation, together with means for releasing 45 one of said members for rotation independently of the other.

The invention also has for an object to provide a novel and improved device of this general character including a plurality of 50 members supported for rotation about substantially a common axis and which members normally rotate in unison, together with means for limiting such unitary rotation of the members, said limit of rotation being determined by a certain identity or character 55 carried by one of the members with respect to an index member supported in juxtaposition to the rotatable members.

An additional object of the invention is

to provide a novel and improved device of 55 this general character embodying means whereby indication is given of the days of the year which fall upon Sunday and which means may also be employed with advantage to indicate legal holidays. 60

The invention consists in the details of construction and in the combination and arrangement of the several parts of my improved computing device whereby certain important advantages are attained and the 65 device rendered simpler, less expensive and otherwise more convenient and advantageous for use, as will be hereinafter more fully set forth.

The novel features of my invention will 70 hereinafter be definitely claimed.

In order that my invention may be the better understood, I will now proceed to describe the same with reference to the accompanying drawings, wherein:

75 Figure 1 is a view in elevation of a computing device constructed in accordance with an embodiment of my invention.

Figure 2 is a longitudinal vertical sectional view taken through the device as illustrated in Figure 1 with certain of the parts 80 in elevation.

Figure 3 is a transverse vertical sectional view taken substantially on the line 3—3 of Figure 2.

85 Figure 4 is an enlarged fragmentary view partly in section and partly in top plan of the adjustable means for limiting the rotation of the main drum in one direction.

90 Figure 5 is a vertical transverse sectional view taken through the device at the longitudinal center thereof and looking toward the left.

Figure 6 is a fragmentary view in perspective illustrating in detail the connection between the release lever and the coacting brake shoe, and

95 Figure 7 is a fragmentary view in plan of the coacting drums and the Sunday or 100 holiday wheel.

As disclosed in the accompanying drawings, B denotes a supporting base substantially rectangular in form and provided with the upstanding marginal flanges 1. 105 Secured to each end portion of the base B at substantially the transverse center thereof are the upstanding brackets 2 provided

at their upper ends with bearings 3 for the elongated tubular shaft 4. One end portion of the shaft 4 is disposed through a sleeve 5 which is disposed through one of the bearings 3, preferably the bearing at the right end of the base B. The shaft 4 is also disposed axially through a drum D, the opposite end portions of which being provided with the spiders 6, each of which include a hub 7 keyed or otherwise engaged with the shaft 4 for rotation therewith.

The inner end portion of the sleeve 5 has keyed or otherwise affixed thereto the hub 8 of a spider 9. The spider 9 carries a relatively short drum D' which is called the "month wheel." The outer end of the drum D' is provided in its periphery with a circumferentially disposed rabbet 10 extending entirely therearound and in which rabbet is arranged a band 11 called the "Sunday or holiday wheel." This band is capable of independent movement circumferentially of the drum D' and is held or maintained in applied position through the instrumentality of the diametrically opposed screws 12 threaded within the outer end face of the drum D' with the heads 12^a thereof partially overlying and contacting with the outer edge of said band 11.

30 The spider 9 includes a pair of oppositely disposed radial spokes to the inner face of each of which is secured an elongated member 14 substantially U-shaped in form. Pivotedly supported at the inner end portion 35 of each of the members 14 is the heel part of a bell crank lever 15, one arm *a* of which extending toward the drum D and the second arm *b* extending toward the shaft 4.

Pivotedly engaged with the free end portion 40 of the arm *b* is a rod 16 extending longitudinally of the adjacent member 14. The outer end portion of said rod 16 is slidably disposed through an inwardly disposed flange or lip 17 provided at the outer end of 45 the member 14. The outer end of the rod 16 normally has frictional contact with the inner face of the peripheral wall of the adjacent end of the drum D so that the drums D and D' are connected for unitary rotation 50 about a common axis.

Each of the rods 16 is constantly urged outwardly through the medium of a retractile member or spring 18 having one end portion secured to the inner end portion of 55 the rod 16 and its opposite end portion secured to a pin 19 or the like supported by the outer extremities of the side flanges 14^a of the member 14 and bridging the space therebetween.

60 The shaft 4 between the hubs 7 and 8 of the spiders 6 and 9 is provided at diametrically opposed points with longitudinally directed slots 20 in communication with the bore of the shaft 4. Slidably mounted on 65 the slotted portion of the shaft 4 is a disk 21

positioned inwardly of the arms *b* of the bell crank levers 15. A pin 22 or the like is disposed radially through the disk 21 and the shaft 4 and which pin locks the disk 21 to the inserted end portion of a rod 23 extending within the bore of the shaft 4 through an end thereof and preferably through the left end of said shaft.

When it is desired to rotate the drum D' independently of the drum D, the rods 16 will be brought out of clutching action on the drum D by pushing the rod 23 inwardly, resulting in the disk 21 engaging the arms *b* of the bell crank lever 15 to cause the desired inward movement of the rods 16. When pressure is taken off of the rod 23, the rods 16 will automatically return into clutching engagement with the drum D under the influence of the retractile members or springs 18.

While ordinarily the members or springs 18 possess sufficient tension to cause the requisite outward movement of the rod 23 when relieved of pressure, I find it of advantage to employ an expansible member or spring 24 inserted within the outer end portion of the sleeve 5 and interposed between the inner end of the rod 23 and a stop 25 intersecting the bore of the sleeve 5 adjacent its outer end.

95 The spider 6 remote from the drum D' is provided with an annular brake flange or wheel 26 with the peripheral wall or face of which coacts the arcuate brake shoe 27, the working face of which being provided with a suitable brake lining 28. The shoe 27 extends upwardly and rearwardly and the lower end portion is pivotally engaged, as at 29, with the adjacent bracket 2.

The brake shoe 27 is constantly urged 105 into contact with the brake flange or wheel 26 by the retractile member or spring 30 anchored at one end to the bracket 2 at a point above the shoe 27 and at its opposite end portions to the pivoted end portion of the releasing rod 31. The inner or lower end portion of the rod 31 is pivotally engaged, as at 32, within a slotted lug 33 extending outwardly and laterally from the shoe 27 at a point substantially midway its length. Upon depression of the rod 31, the shoe 27 will be moved out of engagement or contact with the flange or wheel 26 so that the drum D may be freely rotated.

Extending outwardly from the end of the 120 drum D provided with the flange or wheel 26 is a stop pin 34 which operates to limit the rotation of the drum D in one direction. The lower portion of the adjacent bracket 2 is provided with a pair of horizontally 125 aligned bearings 35 arranged inwardly of the bracket and which rotatably support a threaded shaft 36 which is held against endwise movement in one direction by the bushing 37 fixed to the shaft 36 and contacting 130

with the forward bearing 35 and against movement in the opposite direction by the holding nuts 38 or the like engaged with the shaft 36 and coacting with the rear bearing 35. 39 denotes a plate in threaded engagement with the shaft 36 and which plate is provided with the angular end portions 40 engaged within a trackway 41 whereby said plate is held against rotation around the shaft 36, so that upon requisite rotation of the shaft 36, the plate 39 may be moved as desired lengthwise of the shaft 36. 42 denotes a gravity pawl or dog having its upper end portion pivotally engaged, as at 43, with the plate 39 and said dog or pawl 42 is held against movement in one direction past substantially a vertical center by the outstanding stop lug 44 carried by the plate 39. The lower or free end portion of the dog or pawl 42 intersects the path of travel of the lug 33 carried by the drum D, whereby the rotation of the drum D in one direction is limited yet permitting unhindered or unobstructed rotation of said drum D in the opposite direction.

To facilitate the maintenance of the drum D at its limit of rotation as afforded by the coacting lug 33 and pawl or dog 42, I arrange interiorly of the drum D the rolling weight 45 herein disclosed as an elongated cylindrical bar preferably of metal and which has its end portions engaging the inwardly disposed flanges 6^a carried by the spiders and between the inwardly disposed webs 46 comprised in the spiders.

Anchored by the screws 47 or the like to the end flanges 1 of the base B are the upstanding end plates 48 of requisite dimensions and the forward margins of said plates at the top thereof are provided with the downwardly and forwardly inclined portions 49 defined by the inwardly disposed flanges 50. Secured to the flanges 50 by the screws 51 or the like is an index member M.

The index member M comprises a metallic frame 52 oblong in form and which has mounted therein a glass panel 53. An end portion of the frame 52 adjacent its top is provided with an opening 54 through which the upper end portion of the release rod 31 extends and which end portion of the rod is also disposed through a recess or notch 55 provided in the adjacent flange 50, whereby a support for the upper end portion of said rod 31 is provided.

The rod 31 extends in advance of the index member M and its extended or outer end portion has secured thereto a head or knob 56 to facilitate the depression of said release rod. Adjacent ends of the shaft 4 and the rod 23 extend outwardly of an end plate 48 with the rod 23 terminating outwardly of the shaft 4.

The outer end portion of the rod 23 has

secured thereto a head or knob 57 to facilitate the imposition of pressure on said rod and the extended portion of the shaft 4 has keyed or otherwise affixed thereto an operating wheel or disk 58, the periphery of which being knurled, said disk or wheel providing means to facilitate the requisite rotation of the shaft 4. The sleeve 5 extends through and outwardly of the second end plate 48 and keyed or otherwise affixed to the exterior portion of the sleeve 5 is the operating wheel or disk 59, the periphery of which being also preferably knurled.

The panel 53 is of a length substantially coextensive with the combined length of the drums D and D' so that visual access may be had through the panel 53 to the indicia or characters arranged upon the peripheries of the drums D and D' and the band 11.

Adhesively secured to the inner or under face of the panel 53 are the opaque strips 60 of cardboard or the like and which extend entirely from the left end of the panel 53 to a point slightly inward of the inner end or margin of the drum D'. The inner or opposed edges of the strips 60 are spaced apart to provide an elongated and narrow sight opening 61 through which is adapted to be exposed indicia or characters aligned longitudinally of the drum D. The major portion of the panel 53 overlying the periphery of the drum D' is unobstructed so that visual access may be had to the indicia or characters above and below the sight opening 61 in order to facilitate the adjustment of the drum D' to position the desired indication or characterization in register with the sight opening 61.

The opposed marginal portions of the strips 60 at the right ends thereof are continued to provide the restricted extensions 62 of a length to extend across the indicia or characters upon the periphery of the drum D' and the space between said extensions 62 constitutes a continuation of the sight opening 61.

Disposed circumferentially around the drum D' is a lamination 63 preferably of paper and which has printed or otherwise produced thereon indications or characterizations 64 equidistantly spaced and arranged entirely around the drum D'. The indications or characterizations 64, in the present embodiment of my invention, are divided into twelve series, each series being identified as a month of the year and the indications or characterizations in each series being of a number equal to the number of days in the month said series represents so that the indications or characterizations 64 are three hundred and sixty-five in number or one for each day in a year with the exception of leap year.

Extending circumferentially around the annular band 11 is a lamination 65 inter-

4

sected at regular intervals by the transversely disposed lines 66 printed or otherwise imposed thereon and adjacent lines 66 are spaced apart a distance equal to the space occupied in a circumferential direction by seven of adjacent indications or characterizations 64. The transverse lines 66 are red or any other color different from the color of the indications or characterizations 64 and such lines 66 serve to indicate the dates in any one of the months or in the year which fall upon Sunday. When desired, additional transverse lines may be placed by the operator or other person upon the lamination 65 to indicate what dates of a month or in a year fall upon a legal holiday.

Extending around the periphery of the drum D is a lamination 67 preferably of paper and which is divided longitudinally of the drum D into a plurality of fields herein disclosed as four in number and adjacent fields are separated by the circumferentially disposed lines 68, red or any other desired color. The right marginal portion of the lamination 67 is provided with a narrow field on which is imprinted or otherwise provided a series of characters 69 extending entirely around the drum D in a circumferential direction and which characters are numbered consecutively from "1" to "365," each indicating the number of a day in a year, and which characters are equidistantly spaced and also spaced apart in exact accordance with the spacings of the indications or characterizations 64 hereinbefore referred to.

The strips 60 above and below the sight opening 61 are also divided into fields coinciding with the fields arranged on the lamination 67 carried by the drum D and adjacent fields on said strips 60 are separated by the vertically disposed lines 70, of any desired color but preferably red, and which lines substantially coincide with the lines 68. Each of the fields of the upper strip 60 along its lower marginal portion is provided with a series of equidistantly spaced indications or characters 71 numbered in the thousands consecutively from "1000" to "9000." Each of the fields of the upper strip 60 is provided with interest or percentage indications 72 herein disclosed as ranging successively from "5%" to "8%." The upper marginal portion of the lower strip 60 in each of the fields in vertical alinement with the indications or characters 71 is provided with the indications or characters 73 indicating the rate or percentage of interest for three hundred and sixty-five days of the amount directly thereabove as determined by an indication 71.

Each of the fields of the lamination 67 carried by the drum D is provided with nine longitudinally spaced and circumferentially

disposed indications or characterizations 74, said indications or characterizations being equidistantly spaced with adjacent characterizations spaced apart similar to the characterizations 69. Each series of indications or characterizations 74 consecutively indicates the amount of interest of its field for the days of a year in connection with the sum denoted by an indication 71.

Initially the drums D and D' are connected or clutched together for unitary movement, with the drum D at the limit of its movement in one direction as afforded by the coacting lug 33 and pawl or dog 42. When in this position, the day indication "365" as comprised in the series of characterizations 69, together with the indications or characterizations 74 in alinement therewith in a direction longitudinally of the drum D, are exposed through the sight opening 61. The band 11 is also adjusted to bring a prime line 36 in register with the date on the drum D' of the first Sunday in the year.

To compute the interest due on a note, press inwardly the rod 23 to disengage the rods 16 from the drum D' and then rotate said drum D' through the instrumentality of the wheel or disk 59 to bring the date when the note was made for exposure through the sight opening 61. Then release the rod 23 which will result in the drums D and D' being clutched or locked for unitary movement. Then rotate the shaft 4 through the medium of the wheel or disk 58 until the date on the drum D' on which the note will be paid is exposed through the sight opening 61. This will result in an indication 69 being exposed through the sight opening 61 giving the exact number of days the note has run. Then to the left of the year column will be exposed the indications 74 to the left of the indications 69 exposed through the sight opening 61 will give the interest on amounts from \$1000 to \$9000 at 5%, 6%, 7% and 8%. To get the interest on \$100, move the decimal point one place to the left; for \$10, move the decimal point two places to the left, and for \$1, move the decimal point three places to the left.

It is to be understood that when the drum D is rotated, the releasing rod 31 is depressed to release the brake shoe 27 from engagement or working contact with the brake flange 26. When the requisite adjustment of the drum D, together with the drum D', relative to the sight opening 61 has been effected, pressure is removed from the releasing rod 31, whereupon the brake shoe will automatically return into engagement or working action upon the brake flange 26 or wheel 26 so that said drums will be held in desired position in order to make the requisite computation. After the computation has been made, further depression of the releasing rod 31 will result in the drum 130

D automatically returning to its normal position or with the day characterizaton "365" as comprised in the series of indications 69 returning to its normally exposed position through the sight opening 61 and which automatic return or rotation of the drum D is effected by the rolling weight 45.

It is also preferred that the directions for employing my improved computing device be printed or otherwise imposed upon the lower strip 60.

It is also to be understood that at the end of a year, the band 11 is partially rotated relative to the drum D' to advance the prime 15 transverse line 66 one day. It is also to be understood that in the event of a leap year, after the month of February passes, this band 11 is again adjusted to advance one day the prime line 66, so that the requisite 20 indication of Sundays may be provided.

From the foregoing description it is thought to be obvious that a computing device constructed in accordance with my invention is particularly well adapted for use 25 by reason of the convenience and facility with which it may be assembled and operated, and it will also be obvious that my invention is susceptible of some change and modification without departing from the 30 principles and spirit thereof and for this reason I do not wish to be understood as limiting myself to the precise arrangement and formation of the several parts herein shown in carrying out my invention in practice except as hereinafter claimed.

I claim:

1. A device of the class described comprising two drums arranged end to end and rotatable about a common axis, means for normally locking said drums for unitary rotation, an index member common to both of the drums, a stop pin extending outwardly from an end of one of the drums, a threaded shaft supported adjacent said pin, a plate 45 in threaded engagement with the shaft, means for holding the plate against rotation with the shaft, a dog pivotally engaged with the plate, and means for holding the

dog against movement in one direction past substantially a vertical center, the stop of 50 the drum upon rotation of the drum in one direction engaging the dog to limit the rotation of the drum in such direction, said drum having unhindered rotation by the pawl in the opposite direction. 55

2. A device of the class described comprising a tubular shaft, a drum carried thereby, a second drum positioned adjacent an end of the first named drum and supported for rotary movement, a clutch mechanism carried by the second named drum and coacting with the first named drum and normally engaging said first named drum to cause both of the drums to rotate in unison, and a rod movable within the tubular shaft and coacting with the clutch mechanism to release the same from the first named drum. 60

3. A device of the class described including a rotating element, a movable member supported adjacent said element, means for imparting movement to said member in opposite directions, a dog carried by said member and having limited movement in one direction, a part carried by the rotary element engageable with said dog upon rotation 75 of said element in one direction to limit the extent of rotation of said element, said rotatable member including annular flanges placed longitudinally of its axis, and a rolling weight having its end portions engaging said flanges for imparting movement to the rotating element to bring the part carried thereby into contact with the dog. 80

4. A device of the class described comprising two drums arranged end to end and rotatable about a common axis, means for normally locking said drums for unitary rotation, means extending axially of one of the drums to render the first named means inoperative, an index member common to both 90 of the drums, and means coacting with one of the drums for normally holding the same against rotary movement. 85

In testimony whereof I hereunto affix my signature.

ADOLPH H. C. HORNBOSTEL.
